James P. McEntee

UNITED STATES PATENT OFFICE.

JOHN H. LEGGAT, OF MAISONNEUVE, QUEBEC, CANADA.

COOKING APPARATUS.

1,238,029.

Specification of Letters Patent. Patented Aug. 21, 1917.

Application filed December 15, 1916. Serial No. 137,160.

To all whom it may concern:

Be it known that I, JOHN HALLIDAY LEGGAT, of the town of Maisonneuve, Province of Quebec, Dominion of Canada, a subject 5 of the King of Great Britain, have invented certain new and useful Improvements in Cooking Apparatus; and I do hereby declare that the following is a full, clear, and exact description thereof.

10 Heretofore a serious defect has been experienced in cooking apparatus generally and more particularly the type having a fire-box at one side and an oven heated by the hot gases emanating from the fire-box, 15 from the fact that the ovens could not be uniformly heated, the portion nearest the fire-box being usually very much hotter than the balance of the oven space, the result being that an article of food being cooked in 20 the oven would be liable to be burned at one side before the balance was done. To cure this defect is the object of my invention and I have solved the problem by taking the heated gases from the fire to a point 25 beneath the oven, distributing them over the entire area of the bottom and causing them to flow with substantial uniformity upwardly around the oven to a point at the middle of the top thereof whence they are 30 conducted to the chimney connection.

My improved cooking apparatus comprises, in addition to the fire-box, a flue leading therefrom to a base oven flue beneath the oven and slightly greater in horizontal dimensions than the oven. From this 35 base flue and at each side of the oven a pair of side oven flues lead upwardly to the top of the oven and communicate with the top flue, these side and top flues being equal in 40 measurement to the sides and top of the oven; and from the middle of the top flue a chimney flue leads to the chimney connection. This chimney flue is located in a space 45 between the top of the oven and the top of the apparatus with which space the fire-box communicates and the chimney flue has a pair of damper-controlled ports, one communicating with the top of the oven flue and the other with the portion of the said 50 space between it and the fire-box.

For full comprehension, however, of my invention, reference must be had to the ac-

companying drawings forming a part of this specification in which similar reference characters indicate the same parts, and 55 wherem:

Figure 1 is a transverse vertical sectional view of a stove constructed according to my invention;

Fig. 2 is a vertical sectional view taken 60 on line 2—2 Fig. 1; and

Fig. 3 is a plan view partly in section.

Specifically stated, the preferred embodiment of my invention which is illustrated in the drawings consists of an oven having 65 an arched top 2, sides 3 and 4, bottom 5 and rear walls 6. The fire-box is indicated at 7 and the grate at 8 while the ash-pit is indicated at 9. A vertical wall 10 forms the inner wall of the fire-box and ash-pit. This 70 wall is spaced from the side wall 4 of the oven to present a flue 12 and the opposite side wall 13 of the stove is spaced a corresponding distance from the side 3 of the oven to present a vertical flue 14 at that side, 75 and an arched plate 150 parallel to the top plate 2 of the oven is spaced above the same a distance equal to the spacing of the plates 13 and 10 from walls 3 and 4 thus presenting 80 a top oven flue 15. A space 16 beneath the oven is for distributing the hot gases to both sides of the oven and is preferably of greater cubical measurement than the flues 12 and 14. The fire-box is connected with this distributing space by an angular flue 17 one 85 end 18 of which is at a level to intersect the surface of the grate when the latter is in position supporting the fire, and the opposite end 19 communicates with a port in the middle portion of back plate 6 forming the 90 back of space 16. This flue 17 is of substantially round cross-section and extends from the intake end 18 horizontally to the middle of the rear of the oven and then downwardly in a perpendicular line to its exit end 19. A 95 horizontal plate 20 is located above and in comparative close proximity to the arched plate 150 and at its center there is a port 21 communicating with top oven flue 15. The top 22 of the stove is spaced above the plate 20 to accommodate a flue 26; otherwise this space as indicated at 28 extends without obstruction throughout an area equal to the horizontal dimensions of the oven and oven,

flues 14 and 15. The flues 12 and 14 are collectively equal in capacity to the flue 17, flue 15 or the flue 26. This flue 26 leads from the port 21, with which it communicates, directly to the rear of the stove where it turns toward the fire-box side and communicates with a chimney flue 30. The fire-box side of this flue 26 has a port 27 adapted to effect direct communication between the top of the fire-box flue 26 and the chimney.

The front plate 31 of the stove contains doors 32 and 33 for the oven and ashpit and a cleaning door 34 to allow access to the distribution flue 16. A cleaning door 35 is also provided at the rear of the stove in communication with a receptacle 36 having an inclined bottom 37 and into which soot and particles of partially consumed fuel are precipitated.

The forward end of the flue 26 is in the form of a damper 40, and a slidable damper 41 operated by a pull-rod 42 controls the port 21 and a similar damper 43 operated by a pull-rod 44 controls the port 27.

A damper-controlled port 50 is located in the side wall 51 of the stove and in a position slightly below the grate, and the fire-box is lined with fire-brick 52.

The corners of the distribution flue 16 at each side of the stove, (but not at the front and back), are cut off by plates 55 and 56 respectively to direct the flow from the flue 17 to the flues 12 and 14.

The space between the back-plate 6 of the oven and the rear wall 60 of the stove and surrounding the flue 17 and the receptacle 36, the space cut off by the plates 55 and 56 and the space between the plates 20 and 150 are all packed with asbestos or other heat insulating material thus preventing radiation of any of the heat from the flue 17 between its ends and enabling practically all the hot gases from the fire-box to be delivered to the distribution space 16.

In order to permit the ready frequent cleaning of the side and top flues a scraper 190 of inverted U-form and clasping the top and sides of the oven, has a pair of rods 200 connected thereto and projecting through the front 32. By drawing this scraper forward the soot and ashes which collect on the top and sides of the oven are dislodged and precipitated to the distribution flue where they may be removed by the cleaning door 34.

When it is desired to have a direct draft upon the fire from the chimney the damper 41 is closed and the damper 43 opened when the flow will be upwardly through the grate past the mouth 18, flue 17 to the space 28 through port 27 and along flues 26 and 30 to the chimney; and when it is desired to heat the oven the damper 41 is opened and damper 43 closed thus causing the draft to be through the grate into the flue 17 to the

distributing space 16, flues 12, 14 and 15, port 21 and flues 26 and 30 to the chimney.

This particular arrangement of parts and flues secures either a direct draft from the fire through the space beneath the stove top to the chimney or from the fire-box around the oven to the chimney and in the latter case there is practically a uniform heating of all parts of the oven.

What I claim is as follows—

1. In a cooking apparatus, the combination with a heat generator and an oven; of a comparatively large distributing chamber beneath the oven; a downwardly extending flue at the rear of the apparatus leading from the heat generator to the rear of the heat distributing chamber; a chimney connection; and flues leading from the distributing chamber up each side of the oven to the chimney connection, substantially as described.

2. In a cooking apparatus, the combination with a heat generator located at one side thereof, and an oven, of a distributing chamber beneath the oven; a flue at the rear of the apparatus and leading from the heat generator to the rear of the distributing chamber; a top flue completely covering the top of the oven and having a central port in its top; side flues at the sides of the oven and effecting communication between the distributing chamber and the top flue; a chimney flue, and a flue leading from the central port of the top flue to the chimney flue, substantially as described.

3. In a cooking apparatus the combination with a fire-box located at one side thereof, and an oven; of a distributing chamber beneath the oven; a flue at the rear of the apparatus and leading from the fire-box to the rear of the distributing chamber; a top flue completely covering the top of the oven and having a central port in its top, side flues at the sides of the oven and effecting communication between the distributing chamber and the top flue; a chimney flue; a flue leading from the central port of the top flue to the chimney flue and having a port in the side thereof toward the fire-box and a stove top covering the fire-box and space within which the last-mentioned flue is contained, and dampers controlling the ports.

4. In a cooking apparatus, the combination with a chimney connection, a fire-box located near the top of one side thereof and having a grate, and an oven located between and spaced from the fire-box and the opposite side of the apparatus and the said oven being spaced above the bottom of the apparatus; a plate located above and spaced from the top of the oven and having a central port, a flue leading from the fire-box to a space beneath the oven and having its intake end disposed in close proximity to the grate;

- a flue above the said plate and communicating at one end with the central port therein and at its opposite end with the chimney connection, the said flue having a port in the 5 side thereof toward the fire-box; a stove top covering the fire-box; the oven and the space containing the last mentioned flue, and dampers controlling the said ports, substantially as described.
- 10 5. In a cooking apparatus, the combination with a chimney connection, a fire-box located near the top of one side thereof and having a grate, and an oven located between and spaced from the fire-box and the opposite 15 side of the apparatus the said oven being spaced above the bottom of the apparatus; a plate located above and spaced from the top of the oven and having central port; a flue leading from the fire-box to the space 20 beneath the oven and having its intake end disposed in close proximity to the grate, a horizontal flue above the said plate and communicating at one end with the central port therein and having a port in the side thereof toward the fire-box; a stove top covering the fire-box; the oven and the space containing the last-mentioned flue; dampers controlling the said ports; a chimney flue communicating with the chimney connection 25 and the last-mentioned flue, substantially as described.
6. In a cooking apparatus, the combination with a chimney connection, a fire-box located near the top of one side thereof and having a grate, and an oven located between and spaced from the fire-box and the opposite side of the apparatus and the said oven being spaced above the bottom of the apparatus; a plate located above and spaced from the 30 top of the oven and having a central port, a flue leading from the fire-box to the space beneath the oven and having its intake end disposed in close proximity to the grate, a horizontal flue above the said plate and communicating at one end with the central port therein and having a port in the side 35 thereof toward the fire-box, a stove top covering the fire-box, the oven and the space containing the last-mentioned flue, dampers controlling the said ports, a chimney flue 40 communicating with the chimney connection and having a receptacle at its lower end for soot, etc., and a cleaning door therefor, the said horizontal flue communicating at its rear end with the said last-mentioned-flue, 45 substantially as described.
7. In a cooking apparatus the combination with a chimney connection, a fire-box located at the top of one side thereof and having a grate and having its outer side wall of 50 greater height than its inner side wall; of an oven located between and spaced from the fire-box and the opposite side of the apparatus, the oven being spaced above the bottom of the apparatus and the oven having an 55 arched top; a plate located above and spaced from the top of the oven and extending from the top of the oven and extending from the fire-box to the opposite side of the apparatus and parallel to the arched top and having a 60 central port, a horizontal plate above the last-mentioned plate and extending from the top of the inner wall of the fire-box to the opposite side of the apparatus and having a central port communicating with the 65 central port of the plate first mentioned, a flue above the horizontal plate, a heat non-conducting packing within the spaces surrounding the flue between the top of the oven and the back of the apparatus and between the upper arched plate and the horizontal plate and in the corners of the spaces beneath the oven, and a fire-brick lining for the fire-box, substantially as described.
- In testimony whereof I have signed my 70 name to this specification in the presence of two witnesses.
